INVENTOR

UNITED STATES PATENT OFFICE.

JAMES WARD WOOLLEY, OF NEWARK, NEW JERSEY.

TAG.

1,248,047.

Specification of Letters Patent. Patented Nov. 27, 1917.

Application filed October 4, 1916, Serial No. 123,611. Renewed September 25, 1917. Serial No. 193,218.

To all whom it may concern:

Be it known that I, JAMES WARD WOOLLEY, a citizen of the United States, residing at Newark, in the county of Essex, State of New Jersey, have invented a new and useful 5 Tag, of which the following is a specification.

My invention consists of a tag adapted for the purpose of identification, shipping, address, weight or other indicating matter, the 10 same being formed of an elbow, one limb of which may be inserted into an object or body of material, baled or bundled and interlocked therewith, and the other limb 15 comprising the tag proper which is adapted to occupy a position on the exterior of said body, whereby the matter thereon is visible. Provision is made for additionally securing 20 said tag proper on said body, whereby the device remains comparatively unremovable in position and may arrive at its destination on said object or body without having been detached therefrom.

The invention is satisfactorily illustrated 25 in the accompanying drawing, but the important instrumentalities thereof may be varied, and so it is to be understood that the invention is not limited to the specific details shown and described.

30 Figure 1 represents a perspective view of a tag in normal condition embodying my invention.

Fig. 2 represents a side elevation thereof in operative condition.

35 Figs. 3 and 4 represent perspective views of other forms of the invention.

Similar numerals of reference indicate corresponding parts in the figures.

Referring to the drawings.

40 1 designates the body of a tag, the same being of the form of an elbow composed of the limbs 2 and 3.

The outer terminal of the limb 2 is pointed comprising the spear head 4, and the sides 45 of the limb are serrated comprising the barbs 5. In the lower portion of the limb 3 is the transversely-extending slot or opening 6 which is adapted to receive the locking or securing key 7 which also is provided 50 with the spear head 8 and barbs 9, it having on its outer terminal the finger pieces 10 for convenience in handling said key, the same acting also as flanges which are adapted to abut the limb 3 and limit the key 55 passing entirely through said limb into the

object and disengaging itself from said limb in inward direction.

In Fig. 2 the key is of comparatively U-shape, its legs 11 having spear heads and barbs respectively thereon and the limb 3 60 has a plurality of slots 12 therein to receive said legs.

The operation is as follows:—

The limb 2 is inserted primarily into the material to be tagged, said material being 65 baled or bundled as desired, while the limb 3 rests on the exterior of said material on the side thereof, leaving the outer face of said limb 3 exposed with the address of a shipper, destination, weight, and other matter 70 thereon, it being noticed that the limb 2 interlocks with the material owing to the barbs 5 on the sides thereof, whereby it cannot be withdrawn, but the limb 3 is exposed and may be engaged by surrounding objects 75 and drawn out or bent. To prevent this the limb 7 is passed through the slot 6 or slots 12 and driven into the material parallel 80 with the limb 2 so as to interlock with said material similar to said limb 2 comparatively opposite to the latter and thus the limb 3 is held at both of its ends in position on the material and so controlled thereon under ordinary circumstances without liability to be wrenches from the object. 85

It is evident that when the material is disintegrated, the tag may be released therefrom when it is left in condition for repeated use, the serrations or barbs 5 having 90 been cleared of said material.

In Fig. 4 I show the limbs united by a hinge-like connection as at 13, allowing the limbs to turn on each other for convenience in setting the limbs in position or for other 95 purposes.

It is evident that if desired the outer limb 2 may rest on the exterior of an object or body of material to be tagged, while the spurs, serrations, or barbs 5 are sufficiently salient to engage with said object or body and so hold the limb in position. 100

In this case the face of said limb is sufficiently exposed to have the indicating matter marked thereon in any suitable manner 105 and so presented to view.

Having thus described my invention what I claim as new and desire to secure by Letters Patent, is:—

1. In a tag of the character stated, an el- 110

bow-shaped member formed of primary horizontal and vertical limbs, the horizontal limb thereof having thereon means for interlocking with the object into which said horizontal limb is inserted, the vertical limb being adapted to have its face exposed on the exterior of said object, and a key on said vertical limb adapted to enter said object opposite to said primary limb, said key having thereon means for interlocking it in said object, thus doubly retaining said vertical limb on the object, said key having thereon means for preventing its displacement outward from said object and inwardly from said vertical limb.

2. A tag of elbow form having one limb adapted primarily to enter and interlockingly engage an object, and a key adapted to pass through the other limb and hold the tag in position supplemental to the primary interlocking limb opposite thereto, said key having thereon means for interlocking it in said object, said key having thereon means whereby when it is in operative position in said object it is prevented from displacement from said vertical limb in both outer and inner directions.

3. A tag composed of limbs forming an

elbow-shaped member, one limb thereof preferably the horizontal having thereon means for interlocking it with an object or material in the same, and the other limb thereof being adapted to be exposed on the exterior of said object, and an auxiliary key adapted to be fitted to the latter named limb and passed through the same into said object, said auxiliary key provided with means adapting it to be interlocked in the latter opposite to said horizontal limb against displacement outwardly from said object and inwardly from said vertical limb.

4. A tag of elbow form having one limb adapted to enter and interlockingly engage an object, and a key adapted to enter the other limb and being provided with means adapted to hold the tag interlocked in position in said object supplemental to said primary interlocking limb and opposite to the latter, said key being provided with a stop adapted to abut said vertical limb to prevent displacement of the key inwardly from the latter.

JAMES WARD WOOLLEY.
